[57] CLAIM

The ornamental design for a food waste disposer, as shown and described.

DESCRIPTION

FIG. 1 is a top front perspective view of a food waste disposer showing our new design;

FIG. 2 is a top rear perspective view thereof;

FIG. 3 is a front elevational view thereof;

FIG. 4 is a side elevational view thereof;

FIG. 5 is a rear elevational view thereof;

FIG. 6 is a top plan view thereof; and,

FIG. 7 is a bottom plan view thereof.

The portion shown in broken lines in all views is for illustrative purposes only and forms no part of the claimed design.
